by A. Franklin Bell, Atty.

UNITED STATES PATENT OFFICE.

JOHN R. MAGARVEY, OF SCHENECTADY, NEW YORK.

STEAM BOILER.

Application filed August 27, 1926. Serial No. 131,875.

My invention relates to steam boilers of the tubular type, and its object is to provide means for effecting the connection of the tube or flue sheets to the firebox or combustion chamber, whereby the deterioration of the sheets, due to exposure to the high temperatures of combustion may be substantially overcome.

The improvement claimed is hereinafter fully set forth.

In the present practice of boiler construction, the manner of flanging the tube sheets is such that the heads of the connecting rivets are exposed to the direct heat of the fire, on the rear tube sheet, and to that of the smoke box, on the front tube sheet, the effect of which is to cause their unduly rapid deterioration. My invention is designed to minimize this effect, without involving increased cost of construction, or structural complication.

In the accompanying drawing: Figure 1 is a vertical longitudinal central section through a locomotive boiler, having a combustion chamber, illustrating an embodiment of the invention; Fig. 2, a partial similar section, through a locomotive boiler, not having a combustion chamber, in which the invention is applied; Fig. 3, a half transverse section, through the same, on the line *a a* of Fig. 2; and, Fig. 4, a transverse section, on an enlarged scale, through the firebox tube sheet, on the line *b b* of Fig. 2.

In the practice of my invention, referring descriptively to the specific embodiment thereof which is herein exemplified, and first to Fig. 1, the boiler comprises the usual shell or waist, 1, firebox, 2, combustion chamber, 3, smoke box, 4, rear tube sheet, 5, front tube sheet, 6, and fire tubes, 8. The front tube sheet, 6, is turned, at and adjoining its rim, into a continuous flange, 6^a, which extends inwardly, that is, towards the rear of the boiler, and is secured to the adjacent shell sheet by a seam of rivets, 6^b. The rear tube sheet, 5, is turned, at and adjacent to its rim, into a continuous flange, 5^a, which extends inwardly, that is, towards the front of the boiler, and is secured to the

crown sheet, 2^a, and combustion chamber sheet, 2^b, by a seam of rivets, 5^b. It will be seen that, under this construction, the heads of the rivets, 6^a, and 5^b, are completely protected from the direct access of the heat of the smoke box and the firebox, and that a corresponding exemption from the deterioration resultant upon such direct access of heat, is attained, without increase of structural cost or of the number of connecting rivets.

The application of the invention in a boiler which is not fitted with a combustion chamber, as illustrated in Figs. 2, 3 and 4, differs from that before described, in the particular that the flange, 7^a, of the rear tube sheet, is not inwardly turned, continuously, on the tube sheet, 7, but extends inwardly only from the crown sheet, 2^a, to the point at which the connection of the tube sheet to the shell sheet commences. From this point to the lower end of the tube sheet, the flange is turned rearwardly. In order to ensure a tight joint, welding material, 7^c, is applied on the line upon which the flange is turned in opposite directions.

The invention presents the substantial practical advantages that the riveted seams, being on the water sides of the tube sheets, the cracking of the sheets on the fire side, due to vertical expansion and other causes, will be avoided, and that this result is attained without additional cost of manufacture, or the applications of additional parts.

I claim as my invention and desire to secure by Letters Patent:

In a tubular steam boiler, the combination of a plurality of fire tubes; a front tube sheet, connected to the forward ends of said tubes; a rear tube sheet, connected to the rear ends of said tubes, and having a flange turned inwardly, that is, on the water side thereof, from its top to the commencing point of its connection to the boiler shell, and turned in reverse direction for the remainder of its depth; and rivets, connecting said tube sheets to the boiler structure.

JOHN R. MAGARVEY.
